CAR STOP

James F. McDowell, Kansas City, Kans., assignor to
Wasco Supply Company, Kansas City, Kans., a corporation of Nebraska

Application January 31, 1955, Serial No. 485,011

2 Claims. (Cl. 104—258)

This invention relates to car stops, and more particularly to stops for attachment to rails for stopping of railroad cars.

Heretofore various apparatuses have been used for stopping of railroad cars and the like and the most common have been stops which extend above the rail a considerable distance and have a member for engaging the end of the car for stopping the same, thus providing a bumper against the main portion of the railroad car rather than the wheel.

The principal object of the present invention is to provide a stop attachable to the railroad rails having a gripping action in combination with a wedge member whereby the more pressure exerted on the stop proper by the wheels of the railroad car, the tighter the stop will grip the rail.

Other objects of the present invention are to provide a stop in two pieces having jaws for engaging the head of a railroad rail and having a tapered space between the upper portion of the jaw and the head of the rail to receive a wedge; to provide means for clamping the two piece stop member on the rail; to provide means whereby one of the pieces may be adjusted with respect to the other to fasten the sections together; to provide strengthening ribs on the jaw portion of the stop; and to provide a device of this character which will be self-tightening when contacted by the wheels of the railroad car and one which is simple and economical to manufacture.

In accomplishing these and other objects of the present invention, I have provided improved details of structure, the preferred forms of which are illustrated in the accompanying drawings wherein:

Fig. 1 is a side elevational view showing my stop attached to a railroad rail.

Fig. 2 is a cross-sectional view taken on a line 2—2, Fig. 1.

Fig. 3 is a cross-sectional view taken on a line 3—3, Fig. 2.

Referring more in detail to the drawings:

1 designates a car stop embodying the features of my invention adapted to engage the head of a car rail so that the wheel of a railroad car may contact the same for stopping the car at the desired place. The stop proper comprises two mating sections 2 and 3 having their lower sides elongated and formed so as to provide facing jaws 4 and 5 for engaging the head 6 of a railroad rail 7. It will be noted the lower faces of the jaws provide flanges 8 and 9 which engage the underneath sides of the head as indicated at 10 and 11 for retaining the stop on the rail. The flanges are spaced from the upper portion of the jaws providing a space 12 between the rail and the upper portions of the jaws as indicated at 13. The jaw portions are tapered as illustrated in Fig. 1 so that the space above the rail head will also be tapered for a purpose later shown.

Sections 2 and 3 are provided slightly above the jaw portion thereof with spaced openings 14, 15, 16 and 17

2

for receiving bolts or the like 18 retaining the device on the rail. The sections are elongated and the vertical portions 19 and 19' are somewhat of a triangular shape with one side 20 thereof rounded as indicated at 21 to substantially the shape of a railroad car wheel (not shown) which provides a striking surface for such wheels. The upper portion 22 of the sections is provided with an opening 23 to receive a bolt 24 for clamping the sections together. A plurality of washers 25 are provided for the bolt 24 so that the upper portion of the sections may be spaced and in substantially vertical position as the lower portions thereof due to the possibility of the head of the rails being of different dimensions.

A tapered wedge 26 is provided for engaging on top of the head of the rail in the tapered space 12 of the jaws 4 and 5 of the sections and extends the full length of the jaws as best illustrated in Fig. 1 so that when the wheels of the railroad car strike the portion 21 of the stop member, pressure thereagainst will tend to tighten the jaw members on the wedge and the rail and thus provide a self-tightening structure and prevent the stops from becoming loose on the rail should the nuts of the bolts become loosened or for any other reason.

The slant of the wedge 26 as illustrated in Fig. 3 will tilt the mating sections slightly forwardly so that the striking portion 21 will correspond substantially to the circumference of the wheels of the railroad car. It will be noted two of the bolts 18, which engage in the openings 14 to 17 inclusive, extend through the openings in one direction and the other two bolts in the opposite direction. The openings 15 and 17 in the two are slightly elongated as best illustrated at 27 and 28, Fig. 3, and heads 29 of the bolts engage the section having such elongated openings thus allowing for shifting of the sections to adjust the vertical arrangement of such sections to allow for alignment of the sections. The openings 14 and 16 in the section 3 are also elongated so that the shank of the bolt near the head 29 will engage in such openings. The bolts 18 are known as hack bolts and the shanks are flattened as indicated at 18' to fit the holes 14, 15, 16 and 17 to prevent turning thereof in the openings. The elongated jaw portions 30 and 31 are provided with a plurality of vertical ribs 32 for strengthening the jaws and also to provide a symmetrical structure. There is a substantially triangular opening 33 in the sections and the forward and rear outer edges are also provided with ribs 34 and 35 to add strength to the sections.

It will be obvious from the foregoing that the tapered angles of the wedge and in the wheel stop castings or sections result in a self-tightening action when the stop is contacted by the wheels of a railroad car.

It will further be obvious that I have provided an improved car stop easily and quickly assembled on railroad rails for the purpose set forth.

What I claim and desire to secure by Letter Patent is:

1. A railroad car stop for attachment to the head of a rail having a base flange with an upwardly extending web terminating in a rail head having substantially parallel side faces and bottom surfaces inclined outwardly and upwardly from said web comprising, two mating sections each having elongated lower portions with facing jaw surfaces for engaging the side faces of the rail head, means on said lower portions of the mating sections for engaging the inclined bottom surfaces of the rail head, said mating sections each having vertically extending upper portions offset inwardly from the respective facing jaw surfaces and providing lower faces spaced upwardly from the rail head, said upper portions having a plurality of openings above said lower surfaces, bolt means extending through said openings for securing said mating sections together and clamping the facing jaw surfaces on the side faces of the rail head, means adjacent the upper end of said

upper portions for holding said upper portions in spaced substantially parallel relation when the facing jaw surfaces are in clamping engagement with the sides of the rail head, said mating sections being so constructed that when the means on the lower portions thereof engage the bottom surfaces of the rail head the lower surfaces of the vertically extending upper portions and top face of the rail head define a space tapered longitudinally of the rail throughout the length of the mating sections, said lower faces being inclined laterally inwardly and upwardly from the respective facing jaw surfaces, and a wedge of substantially the same length as the lower portions of the sections and of a width less than the width of the rail head, said wedge having upper and lower surfaces spaced and shaped to correspond to the tapered space between the top of the rail head and lower surfaces of the upper portions of the mating sections whereby tightening of all of the bolt means will clamp the jaw surfaces on the side faces of the rail head and the wedge to the top of said rail head and striking the sections will tighten the sections on the wedge and rail throughout the length of said sections.

2. A railroad car stop for attachment to the head of a rail having a base flange with an upwardly extending web terminating in a rail head having substantially parallel side faces and bottom surfaces inclined outwardly and upwardly from said web comprising, two mating sections each having elongated lower portions with facing jaw surfaces for engaging the side faces of the rail head, flanges extending inwardly from said lower portions of the mating sections and having inclined upper surfaces thereon for engaging the inclined bottom surfaces of the rail head, said mating sections each having vertically extending upper portions offset inwardly from the respective facing jaw surfaces and providing lower faces spaced upwardly from the rail head, said upper portions having a plurality of spaced openings adjacent to said lower surfaces, bolt means extending through said openings

for securing said mating sections together and clamping the facing jaw surfaces in engagement with the side faces of the rail head, means adjacent the upper end of said upper portions for holding said upper portions together 5 in spaced substantially parallel relation when the facing jaw surfaces are in clamping engagement with the side faces of the rail head, one edge of the mating sections having a curved surface substantially on a radius corresponding to the radius of the peripheral surface of a wheel 10 of a railroad car for engagement thereby, said mating sections being so constructed that when the flanges thereon engage the bottom surfaces of the rail head the lower surfaces of the vertically extending upper portions and top face of the rail head define a space tapered longitudinally of the rail throughout the length of the mating sections, said lower faces being inclined laterally inwardly and upwardly from the respective facing jaw surfaces, and a wedge of substantially the same length as the lower portions of the sections and of a width less than the 15 width of the rail head, said wedge having upper and lower surfaces spaced and shaped to correspond to the tapered space between the top of the rail head and lower surfaces of the upper portions of the mating sections whereby tightening of all of the bolt means will clamp the 20 jaw surfaces on the side faces of the rail head and the wedge to the top of said rail head and striking the sections will tighten the sections on the wedge and rail throughout the length of said sections.
